UNITED STATES PATENT OFFICE.

GEORGE E. CRAWFORD, OF SAN FRANCISCO, CALIFORNIA.

ASH RECEIVER.

Application filed June 11, 1925. Serial No. 36,468.

To all whom it may concern:

Be it known that I, GEORGE E. CRAWFORD, a citizen of the United States, residing at San Francisco, in the county of San Francisco and State of California, have invented certain new and useful Improvements in Ash Receivers; and I do declare the following to be a full, clear, and exact description of the invention, such as will enable others skilled in the art to which it appertains to make and use the same.

My invention aims to provide a unique form of smoker's ash receiver, which is provided with novel means for extinguishing cigarette buts and discharging them into a receptacle.

With the foregoing in view, the invention resides in the novel subject matter hereinafter described and claimed, the description being supplemented by the accompanying drawings.

Figure 1 is a top plan view of a device constructed in accordance with my invention.

Figure 2 is a side elevation.

Figure 3 is an end view.

Figure 4 is a vertical sectional view cut longitudinally as indicated by line 4—4 of Fig. 1, showing the normal relation of parts.

Figure 5 is a view similar to Fig. 4 but showing the manner in which a cigarette butt may be extinguished.

Figure 6 is a vertical transverse section on line 6—6 of Fig. 4.

In the drawings above briefly described, the numeral 1 designates a hollow base or receptacle which may be of any desired shape and is preferably provided at one end with a safety match box holder 2. Resting removably upon the base 1, I have shown an ash tray 3 whose bottom is formed with a longitudinal slot 4 over the bottom of the base 1, said bottom of the ash tray preferably declining to the slot as shown. The edges of the tray may well be provided with appropriate rests 5 for cigars or cigarettes.

Disposed longitudinally in the slot 4, is a horizontally elongated cigarette butt support 6 whose ends are provided with trunnions or the like 7 supported by the end walls of the tray 3, said supporting member 6 having a plurality of circumferentially spaced longitudinal flanges 8, two of which are always directed upwardly to receive therebetween a cigarette butt B, as shown

in Fig. 5. A normally vertical lever 9 is mounted at one end of the member 6 and is adapted to be swung downwardly as shown in Fig. 5, to force the butt B against the support 6, so as to extinguish said butt. This lever is provided with a spring-pressed arm 10 which is co-operable with the flanges 8 of the member 6, to rotate this member and discharge the extinguished butt into the receptacle 1, when the lever 9 is again restored to vertical position. Upon depression of the lever 9 from the position of Fig. 4, an inwardly directed finger 11 on the free end of the arm 10, snaps past one of the lowermost flanges 8 of the member 6, and when the lever 9 is righted, said finger moves this flange upwardly, thus rotating the entire support 6 to discharge the extinguished cigarette butt.

In the construction shown, the arm 10 is integral with a horizontal transverse rock shaft 12 to which the lever 9 is secured, said shaft being rockably mounted in appropriate bearings 13 secured to one end of the tray 3. A suitable spring 14 is provided to normally swing the lever 9 to an upright position, and this spring may well surround the shaft 12.

Ashes discharged into the tray 3, may gravitate and descend through the slot 4 into the receptacle 1, and whenever a burning butt of a cigarette is to be placed into the device, it is first laid upon the support 6, whereupon the lever 9 is swung downwardly as shown in Fig. 5, thus crushing the butt and extinguishing the fire. Then, when this lever is righted, the support 6 is turned to another position, so as to discharge the extinguished butt into the base 90 or receptacle 1, at the same time presenting another surface of said support for future use.

Excellent results are obtainable from the general arrangement shown and described and it is therefore preferably followed. However, within the scope of the invention as claimed, modifications may be made.

I claim:

1. An ash receiver and butt extinguisher comprising a tray having an opening in its bottom, a hollow base with which said opening communicates, a cigarette butt support rotatably mounted in said opening, a normally raised butt-pressing member movably mounted adjacent said butt support and adapted to be moved downwardly to force

a butt against said support to thereby extinguish the butt, and means for rotating said support when the pressing member is again raised, thereby depositing the extinguished butt in the hollow base.

2. An ash receiver and butt extinguisher comprising a tray having an elongated slot in its bottom, a hollow base with which said slot communicates, a horizontally elongated cigarette butt support rotatably mounted in said slot on a longitudinal axis, said support having longitudinally circumferentially spaced butt-retaining flanges, a butt-pressing lever normally standing substantially upright at one end of said support and fulcrumed to the tray on an axis transverse to said support, said lever being adapted to be forced downwardly against a cigarette butt on said support to thereby extinguish the butt, and a spring-pressed arm secured to the aforesaid lever and co-operable with the flanges of said butt support to rotate the latter when the lever is raised, whereby the extinguished butt is discharged into the hollow base.

3. A cigarette butt extinguisher and receiver comprising a receptacle, a cigarette butt support rotatably mounted over the

bottom of said receptacle, a normally raised butt-pressing member movably mounted adjacent said support and adapted to be moved downwardly to force a butt against said support to thereby extinguish the butt, and means for rotating the support when the pressing member is again raised, thereby depositing the extinguished butt in the receptacle.

4. A cigarette butt extinguisher and receiver comprising a receptacle, a butt support rotatably mounted on a horizontal axis over the bottom of said receptacle, said support having circumferentially spaced butt-retaining flanges, a butt-pressing lever fulcrumed adjacent said support and normally standing substantially upright, said lever being adapted to be swung downwardly to force a butt against the support, thereby extinguishing the butt, and a spring-pressed arm secured to the aforesaid lever and co-operable with the flanges of the support to rotate the latter each time the lever is raised.

In testimony whereof I have hereunto affixed my signature.

GEORGE E. CRAWFORD.
